UNITED STATES PATENT OFFICE

2,467,990

STEAM TURBINE

Carl Barnes Powledge, Conroe, Tex.

Application June 26, 1947, Serial No. 757,120

1 Claim. (Cl. 60—40)

1

My invention relates to improvements in steam turbines, the primary object in view being to provide a simple form of steam turbine operative by steam jets with greater efficiency than the present day steam turbines.

Another object is to provide a turbine operative as above specified and through a liquid medium augmenting the power transmitted by the steam jets in a manner to render the turbine more efficient than the turbines as commonly constructed.

To the accomplishment of the above, and subordinate objects presently appearing, a preferred embodiment of my invention has been illustrated in the accompanying drawings set forth in detail in the succeeding description, and defined in the claim appended hereto.

In said drawings:

Figure 1 is a view in longitudinal section of my improved steam turbine in the preferred embodiment thereof;

Figure 2 is a view in vertical transverse section taken on the line 2—2 of Figure 1;

Figure 3 is a view in edge elevation of the steam header;

Figure 4 is a view in transverse section taken on the line 4—4 of Figure 1.

Referring to the drawings by numerals, according to my invention, as illustrated, a turbine wheel 1 is suitably fixed at one side thereof on one end of a power transmitting horizontal shaft 2 extended through a tubular shaft housing 3 and journaled adjacent its opposite ends in anti-friction bearings 4 in the ends of said housing 3 retained therein by suitable packing glands 5 secured in place in any suitable manner, not shown. Legs, as at 6, support the shaft housing 3. The turbine wheel 1 is hollow with a preferably transversely rounded rim 7 and, on the side thereof opposite said shaft 2, is formed with an axially tubular nozzle 8 forming an exhaust port 9 as will presently more clearly appear.

Vanes 10, preferably of cupped form, are provided in the turbine wheel 1 on the inner circumferential portion of the rim 7 and are spaced apart equi-distantly around said wheel in the plane thereof. The vanes 10 are designed to face oppositely relative to the direction of rotation of said wheel 1, presently indicated.

A hollow, disc like, steam header 11, preferably convex in cross section, and relatively smaller than the said wheel 1 is provided in said wheel 1 in the medium plane thereof and concentric thereto with its periphery spaced slightly from said vanes 10.

2

Jet forming nipples 12 are formed in the periphery of said header 11 tangentially thereof to eject jets of steam tangentially in the direction of rotation of said wheel 1.

5 An axial, horizontal steam inlet pipe 13 is secured to the side of the steam header 11 facing the exhaust port 9 as by a flange 14 suitably secured to said side of said header, the steam inlet pipe 13 registering with an axial steam inlet port 15 in said side of the steam header 11.

10 A horizontal, exhaust pipe 16, substantially larger in diameter than the steam inlet pipe 13, surrounds said inlet pipe 13 concentrically with one end sleeve over the nozzle 8 for rotation of said nozzle 8 therein.

15 A pair of laterally spaced, circular spiders 17 fixed in the exhaust pipe 16 and through which the steam inlet pipe 13 extends, and is suitably fixed therein, provides for supporting said inlet pipe 13 in the exhaust pipe 16, concentrically thereof, the steam inlet pipe 13 supporting the steam header 11 in the turbine wheel concentrically of the same.

20 Upright brackets 18 support the exhaust pipe 16 by means of annular heads 19 thereon in which said exhaust pipe is suitably fixed, said heads 19 being spaced apart at any desired distance to support said pipe 16.

The steam inlet pipe 13 is designed to be connected, in any suitable manner, to a source of steam supply such as a compressor, not shown. The exhaust pipe 16 is open at the end thereof opposite the end sleeved over the nozzle 8.

25 The turbine wheel 1 is designed to be partly filled with water 19, or other suitable liquid, before starting the same and for instance to the level indicated at 20 in Figure 1.

30 Referring now to the operation of the described invention:

35 Steam is admitted into the steam inlet pipe 13 to pass therethrough, as indicated by the arrows in Figure 1, into the steam header 11 through the steam inlet port 15, such steam issuing in jet form out of the jet forming nipples 12 and impinging initially against the vanes 10 above the water level 20 to impart initial rotation to said turbine wheel in the direction of the arrow in Figure 2. As said wheel 1 gains momentum, the water 19, under the action of centrifugal

40 force, forms a ring like body of water around the inner circumferential portion of the rim 7 of said wheel 1 to a depth, indicated by the full line in Figure 1, such that the steam jets issuing from the jet forming nozzles 12 are submerged in the 45 body of water and act upon said body to cause the

same to revolve and pick up the vanes 10 to drive said wheel 1. As best shown in Figure 1, sufficient water 19' is introduced into the turbine wheel 1 to provide for a ring like body being formed of sufficient depth to submerge the rim of the steam header 11. By having the steam jets discharge into the body of water, loss of power through expansion of the steam is obviated to appreciable extent, thus increasing the efficiency of the turbine. Loss of power through condensation of the steam jets in the body of water is negligible. When the water 19' becomes heated by the steam jets so as to generate steam, such steam, together with any spray formed, finds its way out of the turbine wheel 1 by way of the exhaust port 9 and issues out of the exhaust pipe 16.

The foregoing will, it is believed, suffice to embody clear understanding of my invention, without further explanation.

Manifestly, the invention, as described, is susceptible of modification without departing from the inventive concept, and right is herein reserved to such modifications as fall within the scope of the appended claim.

Having described the invention, what is claimed as new is:

In a turbine of the class described, a hollow turbine wheel provided with internal vanes of cup form spaced around the inner circumference thereof, said wheel being adapted to contain a liquid to form, under the action of centrifugal force, a liquid ring around the inner circumferential portion of the wheel covering said vanes, an exhaust pipe at one side of said wheel rigidly

5 mounted coaxially thereof, an axial tubular exhaust nozzle on said side of said wheel rotatably fitted in one end of said pipe and rotatably supporting said wheel on said side thereof, a relatively smaller diameter pipe extending through said exhaust pipe and nozzle and rigidly mounted in the exhaust pipe in spaced relation to the same and to said nozzle, and a hollow circular header in said wheel fast on one end of said 10 relatively smaller pipe and having peripheral jets arranged tangentially therein and adapted to be submerged in said liquid ring, said relatively smaller pipe being adapted for introducing steam therethrough and through said exhaust pipe and nozzle into said header to issue out of the jets into said wheel and liquid ring to drive the same, said exhaust pipe and nozzle providing for discharge of the steam out of said wheel.
